UNITED STATES PATENT OFFICE.

OTTO C. BUETER, OF BLUE ISLAND, ILLINOIS, ASSIGNOR TO UNITED DRUG COMPANY,
OF BOSTON, MASSACHUSETTS, A CORPORATION OF MASSACHUSETTS.

DESIGN FOR A SOAP CAKE.

48.927.

Specification for Design.

Patented Apr. 25, 1916.

Application filed December 1, 1915. Serial No. 64,601. Term of patent 14 years.

To all whom it may concern:

Be it known that I, OTTO C. BUETER, a citizen of the United States, residing at Blue Island, in the county of Cook and State of Illinois, have invented a new, original, and ornamental Design for Soap Cakes, of which the following is a specification, reference being had to the accompanying drawing, forming part thereof.

Figure 1 is a perspective view of a cake of soap showing my design; and Fig. 2 is a side elevation of the cake of soap shown in Fig. 1.

Among other distinctive features of my new design are, the narrow, parallel, equatorial band around the exterior of the cake, the essentially flat surfaces on the top and bottom of the cake, and the convex curves which connect the flat top and bottom surfaces with the narrow medial band heretofore referred to.

I claim:

The ornamental design for a soap cake, as shown and described.

OTTO C. BUETER.
